[57] **CLAIM**

The ornamental design for a cover for a selective call receiver, as shown and described.

DESCRIPTION

FIG. 1 is a top plan view of a cover for a selective call receiver showing our new design;

FIG. 2 is a bottom plan view thereof;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a top, front, and right side perspective view thereof; and,

FIG. 8 is a top, front, and right side perspective view of a second embodiment of a cover for a selective call receiver showing our new design, the bottom is a mirror image of the top, the rear is plane and unornamented, the difference being the openings on the front right corner.

FIG. 1

FIG. 5

FIG. 4

FIG. 2

FIG. 3

FIG. 6

FIG. 7

FIG. 8
